UNITED STATES PATENT OFFICE.

FRANK B. HINKELBEIN, OF SAN JOSÉ, CALIFORNIA.

OIL OR GASOLENE MEASURING CAN.

SPECIFICATION forming part of Letters Patent No. 662,273, dated November 20, 1900.

Application filed May 13, 1898. Serial No. 680,620. (No model.)

To all whom it may concern:

Be it known that I, FRANK B. HINKELBEIN, a citizen of the United States, residing at San José, in the county of Santa Clara and State 5 of California, have invented certain new and useful Improvements in Oil or Gasolene Cans; and I do hereby declare the following to be a full, clear, and exact description of the invention, such as will enable others skilled in 10 the art to which it appertains to make and use the same.

My invention relates to improvements in oil and gasoline cans; and the object is to provide a simple, convenient, and effective 15 can of this class.

To this end the invention consists in the construction, combination, and arrangement of the device, as will be hereinafter more fully described, and particularly pointed out 20 in the claim.

The accompanying drawings show my invention in the best form now known to me; but many changes in the details might be made within the skill of a good mechanic 25 without departing from the spirit of my invention as set forth in the claim at the end of this specification.

The same reference characters indicate the same parts of the invention in the several 30 views.

Figure 1 is a perspective view of my improved oil or gasoline can. Fig. 2 is a vertical section. Fig. 3 is a detail horizontal section. Fig. 4 is a detail view of the vent-cap. 35 Fig. 5 is a vertical detail section through the tubes 6 and 11 and their elbows 8 and 8'.

In the drawings, 1 denotes the body of the can being provided with a raised bottom 2 and a recessed top 3.

40 4 represents the faucet for withdrawing the contents of the can.

5 denotes a vertical groove or recess formed in the front wall of the can and extending from the top to the bottom to receive the gage-glass 6, the upper end of which is connected to the elbow or return-pipe 8, having its opposite end extending through the top of the can, so as to communicate with the interior thereof. The lower end of the gage-glass is 45 removably secured in an elbow 8', the other

leg of which projects through the bottom of the can and communicates with the lower end of the tube 11, and 9 denotes a plug fixed to the lower end of the rod 10, which extends through said tube 11 in the can, and its projecting end is provided with a knob or handle 12, by means of which the plug may be conveniently raised and lowered to open and close the orifice a. This will be found convenient to close the orifice a should it be necessary to replace the gage-glass. The glass tube or gage-glass is made removable from the vertical groove 5 in the wall of the can and is secured to the upper and lower elbows 8 and 8' by means of internally-threaded 55 rings b and c, which may be turned to disconnect said elbows from said gage-glass 6 and the elbow 8' shifted to permit the gage-glass to be removed from the groove 5 in the wall of the can.

As shown in Fig. 5, the gage-glass 6 is surrounded with rubber packing rings b' b', which serve to make a tight joint at the upper and lower ends of said tube 6 between said tube and the rings b and c when the latter are turned to place. In order to remove the glass tube 6 from its seats in the said rings b and c, the ring c must be unscrewed until it moves or screws down upon the threaded portion of the elbow 8' and becomes free 60 from the lower end of said tube 6, at which time the elbow 8' can be turned outwardly on the arc of a circle, the tube 11 turning in its seat to permit said elbow 8' to be swung out from beneath the lower end of said glass gage 6, which will then drop or fall out of its seat and if broken can be replaced by a new gage-glass. The elbow 8' is then turned back beneath the lower end of said gage-glass 6, and the ring c is turned back, carrying the rubber ring b' with it, thereby securing the glass tube in place on the can.

A suitable packing is placed around the tube 11 at the point where the same passes through the bottom of the can to prevent leakage at that point.

13 denotes a vertical scale formed on the front wall of the can and extending around behind the gage-glass, and it is accurately divided to indicate quarts and gallons or frac- 95 100

tions thereof, and 14 represents a vertical guide-rod fixed to the top and bottom beads of the can and parallel with the gage-glass.

15 denotes a pointer or indicator provided with a knob or handle 16 and snugly encompassing said guide-rod, so as to be freely moved up and down the scale.

17 represents a screw-cap removably secured to the elbow 8 and in vertical line with 10 the gage-glass 6, so that when said cap is removed a swab or plunger may be inserted in the gage-glass for the purpose of cleaning the same without removing it from the can.

18 denotes a removable screw-cap by means 15 of which the can is filled, and it is provided with a air-vent plug 19, which closes a conical plug-seat 20, formed in the cap, while the plug 19 is provided with a vertical stem 21, which extends through said cap and terminates in a knob or handle 22 for conveniently manipulating the plug when the faucet is used to withdraw the contents.

A very simple manner of using the can is to set the pointer 15 on the scale at such a 25 distance below the level of the oil or gasoline in the can as will correspond to the capacity of the vessel to be filled. The vessel is then placed under the faucet, which is turned on, and when the level of the oil in the can has

fallen to the mark indicated by the pointer 30 the faucet is turned off without any danger of overflowing the vessel.

While I have shown the body of the can as cylindrical in form, it is obvious that the principles involved may be applied to a can 35 of any other shape.

Having thus described my invention, what I claim as new and useful, and desire to secure by Letters Patent of the United States, is—

In a can of the class described, the can 1 provided with the recessed top and raised bottom, the elbow 8 fixed in the top, the elbow 8' fixed in the bottom, the gage-glass connecting the elbows, the tube 11 communicat- 45 ing with the inner end of the elbow 8' and provided with the orifice a, the plug 9 having a vertical movement in said tube and the rod 10 connected to said plug and having its free end projecting through the top of the can, 50 substantially as shown and described.

In testimony whereof I have hereunto set my hand in presence of two subscribing witnesses.

FRANK B. HINKELBEIN.
